UNITED STATES PATENT OFFICE.

JOSEPH B. STRAUSS, OF CHICAGO, ILLINOIS.

SHIP.

Application filed April 6, 1923. Serial No. 630,387.

This invention relates to improvements in ships and has for its object to provide a new and improved device of this description. Another object of the invention is to provide a ship frame capable of resisting shear and moments longitudinally. Another object of the invention is to provide a ship frame which will be strong enough to prevent its collapse from structural weakness when being handled. Another object of the invention is to provide a frame particularly adapted for dirigible airships. The invention has other objects which are more particularly pointed out in the accompanying description.

Referring now to the drawings:

Fig. 1 is a side view of one form of device embodying the invention showing the front end of the frame.

Fig. 2 is a perspective view showing the front end of the frame.

Fig. 3 is an enlarged view as seen in the direction of the arrows on line 3—3 of Fig. 1.

Fig. 4 is a sectional view taken on line 4—4 of Fig. 1 showing one of the gas cells.

Like numerals refer to like parts throughout the several figures.

Referring now to the drawings;

I have shown a ship having a frame provided with a series of inclined, transverse members 1 having a space within their peripheries, these members being connected together at suitable points so as to form a peripheral truss. In the construction shown these transverse members are inclined alternately in opposite directions and the adjacent members are connected together as clearly shown in Figs. 1, 2 and 3. There are a series of longitudinal members 2 which are connected to the transverse members 1. I prefer to connect the longitudinal members to the transverse members at the points where the transverse members are connected together as, for example, at the points 3 and 4. This is more clearly shown in the diagrammatic, perspective view of Fig. 2. Any suitable means may be used for connecting these members together. I have shown in Fig. 3 an enlarged view illustrating one form. In this view the transverse members 1 and the longitudinal member 2 are connected together by the connecting piece 5 which is connected to both of them. It will

be noted that in this construction the members 1 and 2 are laced or trussed members,

consisting of separated members connected together by diagonals to form a truss or girder construction. I may also provide circumferential members 6. When the device is used in connection with a dirigible airship, the buoyancy may be secured in any desired way as, for example, by providing gas cells 7. For such a construction the transverse members 1 are of the proper shape to permit these cells to occupy the space about which they extend. At the bottom of the device I provide suitable bracing members 8, 9 and 10 as clearly shown in Fig. 4. The transverse and longitudinal members when connected together as herein shown take bending and shear as a truss. This gives the frame great strength longitudinally so that it can be handled, thereby permitting not only the safe handling but preventing the collapse of the structure from weakness when it is used in connection with a dirigible airship. A suitable inclosing shell is provided which is held in place by the longitudinal and transverse members. The transverse members 4 when extending entirely around the structure as in the case of a dirigible are non-circular as they are elongated or elliptical in shape. This structure not only gives great rigidity longitudinally of the structure, regardless of its length, but so transmits and takes care of the moments and stresses as to provide a dirigible frame which meets the requirements presented, both of strength and safety.

I have described in detail a particular construction embodying the invention but it is of course evident that the parts may be varied in many particulars without departing from the spirit of the invention as embodied in the claims hereto appended and I, therefore, do not limit myself to the particular construction shown.

I claim:

1. A ship comprising a frame having a series of inclined, transverse members having a space within their peripheries, said inclined members arranged in pairs, the members of each pair crossing each other near the middle, so that portions of one project beyond portions of the other, said members connected together at the crossing points to form a peripheral truss and longitudinal members connected to the peripheries of said transverse members.

2. A ship comprising a frame having a series of inclined, transverse members hav-

ing a space within their peripheries, said inclined members arranged in pairs, the members of each pair crossing each other near the middle, so that portions of one project 5 beyond portions of the other, said members connected together at the crossing points to form a peripheral truss and longitudinal members connected to the peripheries of said transverse members and an enclosing 10 shell secured to said transverse and said longitudinal members to form an inclosed space.

3. A ship comprising a frame having transverse inclosing members extending across the breadth of the ship from side to side, said transverse members arranged in 15 pairs and inclined alternately in opposite directions the members of each pair crossing each other near their middle and being connected together, at their crossing points a series of longitudinal members connected to 20 said transverse members, the construction formed to provide a space between the crossing parts of the members on each side, the 25 whole forming a rigid frame surrounding said space.

4. A ship comprising a frame having transverse inclosing members extending across the breadth of the ship from side to side, said transverse members arranged in 30 pairs and inclined alternately in opposite directions the members of each pair crossing each other near their middle and being connected together, at their crossing points a series of longitudinal members connected to 35 said transverse members, the construction formed to provide a space between the crossing parts of the members on each side, the whole forming a rigid frame surrounding 40 said space and inclosing sections secured to said framework to inclose said space.

5. A ship comprising a frame having inclosing members extending across the breadth of the ship, said members arranged 45 in pairs and inclined alternately with relation to the axis of said ship, the members of each pair crossing each other near their middle and being connected together at their crossing points, longitudinal members extending along 50 said transverse members and connected thereto at the points where the transverse members are connected together,

whereby said members may take bending and shear as a truss.

6. A ship comprising a frame having inclosing members extending across the breadth of the ship, said members arranged in pairs and inclined alternately with relation to the axis of said ship, the members of each pair crossing each other near their 55 middle and being connected together at their crossing points, longitudinal members extending along said transverse members and connected thereto at the points where the transverse members are connected together, 60 whereby said members may take bending and shear as a truss and an inclosing shell held in place by said members.

7. A ship comprising a frame having a series of circular transverse members and a 70 series of non-circular transverse members, the non-circular members arranged in pairs and being inclined with relation to each other and with the axis of said ship, the non-circular members of each pair crossing 75 each other near their middle and being connected together at their crossing points, longitudinal members connected with said non-circular members at the points where they are connected together whereby the 80 transverse and longitudinal members act as a truss to resist all the forces coming on the ship.

8. A ship comprising a frame having a series of circular transverse members and a 85 series of non-circular transverse members, the non-circular members arranged in pairs and being inclined with relation to each other and with the axis of said ship, the non-circular members of each pair crossing 90 each other near their middle and being connected together at their crossing points, longitudinal members connected with said non-circular members at the points where they are connected together whereby the 95 transverse and longitudinal members act as a truss to resist all the forces coming on the ship, an enclosing shell secured to said transverse and longitudinal members and gas cells contained within them.

Signed at Chicago, county of Cook and State of Illinois, this 16th day of March, 1923.

JOSEPH B. STRAUSS.
